Inventor:

M. Vergnes

UNITED STATES PATENT OFFICE.

MAURICE VERGNES, OF NEW YORK, N. Y., ASSIGNOR TO HIMSELF AND
ALPHONSE PERRIN.

IMPROVEMENT IN LUBRICATING-CUPS FOR STEAM-ENGINES.

Specification forming part of Letters Patent No. 58,354, dated September 25, 1866.

To all whom it may concern:

Be it known that I, MAURICE VERGNES, of the city of New York, in the county of New York and State of New York, have invented a new and Improved Lubricating-Vessel for Steam-Engines, &c.; and I do hereby declare that the following is a full, clear, and exact description thereof, and of its mode or manner of operation, reference being had to the accompanying drawings, and to the letters of reference marked thereon; and making a part of this specification.

The nature of my invention consists in a lubricating-vessel for use in steam-engines and elsewhere, and by which oil can be supplied to the piston of an engine while the engine is in motion, and without any such arrangement or combination of stop-cocks, faucets, &c., as are required in lubricators such as are used generally.

Figure 1 is a general view of the entire vessel or lubricator. Fig. 2 is a vertical sectional view of the same. Fig. 3 is a detached view of one of the plates of the lubricator.

Such improved lubricator or lubricating-vessel is constructed substantially as follows: A stem or tap of metal, A, the lower end of which is to be screwed or fastened into the cylinder, passes through and forms the center of the lubricator, and to the top of such piece of metal is fitted the cup B. The lower part of such stem or tap A is also fashioned or fitted with a projecting part, C, or its equivalent, to give support to the central movable oil-vessel hereinafter mentioned. In the upper end of such stem or tap, and usually central therein, is made an opening or oil-passage, a, which extends into such stem A sufficiently far, so that the side passages or openings, a' a', drilled from the opposite sides of such stem A and connecting with the central passage, a, will open into the central movable oil-vessel referred to. Such oil-passage a opens also into the oil-cup B at the top. In the lower end of such stem A a similar oil-passage, b, is made, extending upward or into such stem far enough to also connect, by means of side connections similar to the ones a' a', with the same central movable oil-vessel. The side openings or passages, a' a', and those similar thereto opening

into the lower passage, b, of the stem A, are placed directly over each other in such stem.

Below the oil-cup B, and supported by and turning on or around the stem A, and between the fixed plates c and d, is a second or central oil vessel or chamber, E, which is moved backward and forward by the handles or arms D D'. Such central or movable oil-vessel, E, is entirely close, except that in the inner side, f, which surrounds and lies against or near to the stem A, there are, near the top of such vessel, suitable openings 1 1, to connect with the oil-passages a' a'; and at right angles thereto, or nearly so, there are also, near the bottom of such vessel E, other openings, 2 2, to connect with the passages leading to the oil-passage b. In the top of such vessel E there are also one or more openings, 3 3, which in certain positions of such vessel open into the recesses g g in the plate c.

When the central oil-vessel, E, is in the position shown in Fig. 2—that is, when the handles or arms D D' are in line with the openings g g in the plate c—the openings 1 1 are in line with or connect with the oil-passages a' a', and the openings 3 3 are also in connection with or open into the recesses g g. If oil is then poured into the cup B, it will pass into the vessel or chamber E, and the air in such vessel will at the same time escape through the openings 3 3 and recesses g g. A partial revolution of the vessel E, so as to bring or place the arms D D' at right angles with the openings g g, shuts off communication between the side passages, a' a', and the openings 1 1, and also between the openings 3 3 and the ones g g, and the oil is retained in the vessel E, ready for use. When it is desired to supply oil to the piston in the cylinder the vessel E is revolved still farther by the arms D D', and to the limits of its allowed movement, which is such as to bring the openings 2 2 in connection with the side passages, which connect with the oil channel or passage b, when the oil flows into the cylinder and upon the piston.

The arrangement and location in respect to each other of the side passages at the top and bottom of the stem and of the passages at the top and bottom of the vessel E may be changed or transposed, it being only necessary that

they should be so arranged that when the passages are opened, so as to fill the vessel E with oil, the lower passages shall not be in communication, and when the latter are in communication, so as to supply the oil to the cylinder, the former ones should not be in communication.

The openings *g g* in the plate *c* are made of considerable length compared with the size of the openings 3 3, so that as the vessel E is revolved such openings 3 3 will communicate or open into the passages *g g* some little time before the openings 1 1 reach the passages *a' a'* and communication is opened with the oil-cup B. If, therefore, at any time, the cup B is filled with oil while the oil-vessel E is in communication with the cylinder, and consequently filled with steam, when such vessel is turned backward the steam will not throw the oil from the cup, but such steam will escape through the openings 3 and *g* before communication is opened with the cup B.

The handles D D connect with the vessel E by a screw-tap, which passes entirely through the sides of such vessel, and which is considerably larger than any of the openings 1, 2, or 3 leading from such vessel. This manner of connecting or inserting the handles into such oil-vessel furnishes an easy and convenient

method of cleaning the cup or vessel E when filled with thickened oil or other matters, it being only necessary to take out one or both handles, when the steam will at once blow out any matters that may be collected in such vessel.

In the construction of such lubricating vessel or machine no stop-cocks or faucets of any kind are necessary or required either for regulating the admission of oil to the central vessel or from it to the cylinder; and the whole construction and arrangement is simple in operation and not likely to get out of order.

What I claim as my invention, and desire to secure by Letters Patent, is—

1. The arrangement of the movable oil vessel or reservoir E, in combination with the cup B and oil-passages *a* and *b* and their connections with such reservoir E, the whole arranged and operating substantially as and for the purposes set forth.

2. The arrangement of the openings *g g* in the fixed plate *c*, in combination with the openings 3 3 in the oil-vessel E, substantially as and for the purposes set forth.

M. VERGNES.
